United States Patent Office

Des. 180,079
Patented Apr. 16, 1957

180,079

CASE FOR TABLEWARE OR SIMILAR ARTICLES

Irving Harper, New York, N. Y., assignor to Chas. D. Briddell, Inc., Crisfield, Md., a corporation of Maryland

Application November 23, 1955, Serial No. 39,029

Term of patent 14 years

(Cl. D58—13)

Fig. 1.

Fig. 2.

Fig. 3.

Figure 1 is a top plan view of a case for tableware or similar articles showing my new design;

Figure 4 is a perspective view thereof in open position, a portion being broken away for convenience of illustration.

I claim:

The ornamental design for a case for tableware or similar articles, as shown.
